UNITED STATES PATENT OFFICE

2,203,037

TRUSS

William P. Walter, Massillon, Ohio

Application August 24, 1938, Serial No. 226,527

2 Claims. (Cl. 128—122)

This invention relates to trusses, and more particularly to an improved means for mounting the truss pad on the frame.

An object of this invention is to provide an improved means whereby the truss pad may be adjusted along the length of the truss frame.

Another object of this invention is to provide a means whereby the pad may be adjusted toward or away from the frame so that any desired pressure may be applied to the rupture.

A further object of this invention is to provide an improved mounting means for the pad whereby the angular relation of the pad relative to the frame may be varied at will to meet the particular condition.

A still further object of this invention is to provide in a truss structure an improved means for attaching the pad to the frame so that the pad may be securely locked in its adjusted position relative to the frame.

With the foregoing and other objects in view, the invention will be more fully described hereinafter, and will be more particularly pointed out in the claims appended hereto.

25 In the drawing, wherein like symbols refer to like or corresponding parts throughout the several views:

Figure 1 is a fragmentary rear elevation of a truss frame having a pair of truss pads secured thereto according to an embodiment of this invention.

Figure 2 is a detail top plan of the structure shown in Fig. 1.

Figure 3 is an enlarged sectional view taken 35 on the line 3—3 of Fig. 1.

Referring to the drawing, the numeral 10 designates generally a frame structure, which includes a relatively rigid frame bar 11 which is bent longitudinally as shown in Fig. 2, and a pair of straps 13 which are adapted to substantially encircle the body of the wearer.

The frame bar 11 is provided with a pair of elongated slots 12, and a pair of pad adjusting and holding bolts 14 are engageable through the slots 12, there being one bolt 14 in each slot 12. A pair of truss pads 15 are mounted one on each bolt 14, and each pad member 15 is provided with a cup or concavo-convex shaped plate member 16 which is secured to the pad 15 by means of 50 bolts, screws or other fastening devices 17. Each plate member 16 is provided with a flange 18 through which the fastening devices 17 are adapted to engage.

A nut member 19 is threaded onto the bolt 55 14, and this nut member 19 is provided with a

convex inner surface 20 engaging in the concave portion of the cup member 16, so that the cup member 16 and the pad 15 may be angularly adjusted relative to the bolt 14 and to the frame bar 11. A spring 21 is disposed about the inner end of the bolt 14, and one end of the spring 21 engages against the inner face of the pad 15 within the cup member 16 and the other end of the spring 21 engages against the nut member 19 10 so as to frictionally hold the nut member 19 against turning and thus permit desired turning of the bolt 14 so as to effect adjustment of the pad 15.

A tubular or cylindrical sleeve member 22 is 15 loosely disposed about the bolt 14 and is provided with peripheral threads 23. A second sleeve or nut 24 having interior threads is threaded onto the sleeve 22, and this sleeve or nut 24 provides a means whereby the pad 15 may be adjusted toward or away from the frame bar 11. A washer 20 25 is interposed between the head of the bolt or screw 14 and the adjacent side of the frame bar 11 and on the side opposite from the sleeve 22.

In the use of this truss structure, the frame 10 is disposed about the body of the wearer, and 25 the sleeve or nut member 24 is initially adjusted along the length of the sleeve 22 by turning the nut 24 in the proper direction. The exterior surface of the nut or sleeve 24 may be knurled or serrated so as to facilitate the turning thereof. 30 The angular position of the pad 15 may then be adjusted by rocking the pad and cup member 16, whereupon the bolt 14 may be turned to tightly bind the cup member 16 between the nut 19 and the nut or sleeve 24. The tightening 35 of the bolt 14 will not only bind the sleeve or cup member 24 on the sleeve 22, in addition to locking the pad 15 in its adjusted position, but will also lock the bolt 14 in the desired position 40 along the length of the slot 12.

In this manner the pad 15 may be adjusted lengthwise of the frame 14 and locked in its adjusted angular position as well as its extended position relative to the frame 11. It will, therefore, be seen that the truss pad 15 may be disposed in any desired position relative to the frame bar 11 and such adjustment may readily be effected by the wearer through the medium of a screwdriver.

It will also be apparent that one of the truss pads 15 may be adjusted independently of the other truss pad 15, and readily locked in its adjusted position. While I have shown a truss structure embodying two truss pads, it will be 55

understood that if desired only one of these pads may be used.

The material of which the pad 15 is constructed may be varied to suit the particular ailment or condition, and it will also be understood that the concave face 26 of the pad 15 may be changed to suit the particular condition.

The pad member 15 is preferably provided with an air cushion member 27 in the form of a hollow parti-spherical body having an opening in the center thereof so that this body may readily move to an extended position shown in full lines in Fig. 3. The inner end of this member 27 is provided with a bead engaging about the periphery of the solid button member 15, the bead yieldingly holding the body 27 upon the button 15. The air cushion member 27 may be secured to any base or button construction, either as a part of said base or attached thereto if said base is sufficiently rigid to support said member 27 and can be attached to the truss frame 10.

When the device is in applied position the cushion member 27 will flex to substantially the dotted line position shown in Fig. 3, trapping a quantity of air therein so that a yieldable and soft cushion is provided for contact with the injured part, and this yieldable body will flex under undue strains so that the injured part will not be unduly affected by such undue strains. Preferably the body 27 tapers in thickness from the inner toward the outer end thereof so that the thicker portion thereof will yieldingly resist collapsing of the body.

What is claimed is:

1. In a truss, an elongated rigid frame bar, a cup-shaped pad carrier member, a bolt engaging through said bar and having an end portion thereof disposed within said cup-shaped member, a nut threaded onto said bolt and engaging within the concave side of said cup-shaped member, and means engaging the convex side of said cup-shaped member and said bar and engaging about said bolt to lock said member in angularly adjusted position relative to said bar while holding said member in adjusted spaced relation to said bar. 5

2. In a truss, an elongated rigid frame bar, a concavo-convex pad carrier member, a threaded bolt engaging through said bar and having an end portion thereof disposed within said concavo-convex member, a nut threaded onto said bolt engaging within the concavo-convex member and having a convex surface engaging the concave side of said concavo-convex member, a cylindrical sleeve loosely disposed about said bolt, said sleeve having peripheral threads, and an annular nut threaded onto said sleeve and engaging the convex side of said concavo-convex member and coacting with said first nut to hold said pad carrier member in angularly adjusted position relative to said bar while simultaneously maintaining said pad carrier member in spaced relation with respect to said bar. 10 15 20 25 30
